UNITED STATES PATENT OFFICE.

HENRY F. GOETZ, OF WATERBURY, CONNECTICUT, ASSIGNOR TO WATERBURY MFG. CO., OF WATERBURY, CONNECTICUT, A CORPORATION.

JEWEL-CUP.

1,039,516.

Specification of Letters Patent. Patented Sept. 24, 1912.

Application filed December 18, 1911. Serial No. 666,546.

To all whom it may concern:

Be it known that I, HENRY F. GOETZ, a citizen of the United States, residing at Waterbury, in the county of New Haven 5 and State of Connecticut, have invented a new and useful Improvement in Jewel-Cups; and I do hereby declare the following, when taken in connection with the accompanying drawings and the letters of reference marked thereon, to be a full, clear, and exact description of the same, and which said drawings constitute part of this specification, and represent, in—

Figure 1 a view in side elevation of a 15 jewel-cup constructed in accordance with my invention. Fig. 2 a view thereof partly in elevation and partly in vertical central section. Fig. 3 a detached broken plan view of the central portion of the cup-body. Fig. 20 4 a detached plan view of the coupling washer. Fig. 5 a detached broken plan view on an enlarged scale of the cup with its lining removed, and showing the interlocking of the cup-body with the hollow standard of 25 the cup through the medium of the washer. Fig. 6 a broken view in vertical central section on the line *a—b* of Fig. 5.

My invention relates to an improvement 30 in bath room accessories, and more particularly to cups designed to be used as jewel cups, as soap dishes, or as tumbler cups, according to their specific form and location, the object being to produce at a reasonable cost a compact and attractive article constructed with particular reference to cheapness of manufacture, ease of being kept 35 clean, and capacity to take a high finish.

With these ends in view, my invention 40 consists in a cup having certain details of construction and combinations of parts as will be hereinafter described and pointed out in the claim.

In carrying out my invention as herein 45 shown, I produce from a single piece of sheet-metal a cup-lining 2, having its edge rolled over to form a bead 3 receiving the edge of a sheet-metal cup-body 4 which substantially corresponds in diameter to the cup-lining 2 but is a trifle deeper than the 50 same, the said cup-body being formed with a central circular opening 5 entered by three integral fingers 6 arranged equi-distant from each other. The inner edge of the cup-body 4 rests upon a shoulder 7 formed at the 55 upper end of a tubular standard 8 formed

with circumferential ornamental grooves 9 and 10 located one above the other, and having its lower end reduced in diameter to form a stem 11 which is externally threaded to permit the cup to be readily mounted. At 60 its open upper end the standard 8 is formed with a retaining flange 12 which is passed upward through the opening 5 in the cup-body 4 and spun outward so as to be turned down upon the retaining fingers 6 of the 65 cup-body, as shown in Fig. 6. There are three of these fingers, and they are passed through three out of six notches 13 formed in the flat sheet-metal coupling washer 14 which is seated upon the upper face of the 70 cup-body so as to be concentric with the circular opening 5 therein. In this way the washer 14 is held against rotation with respect to the cup-body 4, while the cup-body 4 is held against rotation with respect to 75 the standard 8 by bits of solder 15 which are dropped into the three notches 13 not occupied by the fingers 6 of the cup-body, these bits of solder 15 being shown in Fig. 5. The washer, it will be seen, reinforces the 80 joint between the cup-body 4 and standard 8.

In producing my improved jewel cup, the washer 14 is first positioned upon the bottom of the cup-body 4 with three of its notches 85 13 in registration with the three fingers 6 of the cup-body. The said fingers 6 are now bent upward into the said notches and then outward therein, as shown in Fig. 6 so as to couple the washer and cup-body. The flange 90 12 of the standard 8 is now passed through the circular opening 5 of the cup-body after which the said flange 12 is spun over and outward upon the bent fingers 6 as shown in Fig. 6. Bits of solder 15 are now dropped 95 into the vacant notches 13 in the washer 14 after which the lining 2 is positioned and its bead 3 turned over upon the outer edge of the cup-body 4.

I claim:—

In a jewel cup, the combination with a cup-body having a central circular opening formed with a plurality of inwardly projecting coupling fingers, of a washer arranged upon the upper face of the said body concentric with the opening therein and formed with a plurality of notches spaced with reference to the spacing of the said fingers, of which there are more notches than fingers, and a hollow standard 105 pro- 110

vided at its upper end with a retaining flange adapted to be passed upward through the central opening in the cup-body, and to be spun outward over the said fingers when they are turned upward and outward in notches in the said washer.

In testimony whereof, I have signed this

specification in the presence of two subscribing witnesses.

HENRY F. GOETZ.
